Harris

UNITED STATES PATENT OFFICE

FREDERICK C. BLANCHARD, OF DORCHESTER, MASSACHUSETTS

LUBRICATING SYSTEM

Application filed February 8, 1929. Serial No. 338,546.

This invention relates to automatic lubricating systems, for application to industrial and other machines of various kinds, such as machine tools, wood working machinery, rubber mills, textile machinery, crushing and pulverizing mills, laundry machines, pumps, paper machinery, sugar mills and printing presses.

The invention will be best understood by reference to the following description, when taken in connection with the accompanying drawings of one specific embodiment thereof, while its scope will be more particularly pointed out in the appended claims.

In the drawings:

Fig. 1 is an elevation, partly in vertical section, of a lubricating system exemplifying the invention;

Fig. 2 is a vertical, sectional view, on an enlarged scale, of one of the feeders of the system;

Fig. 3 is a sectional view, substantially on line 3—3 of Fig. 2, certain parts being shown in elevation;

Fig. 4 is a plan, partly in horizontal section, illustrating the pumping unit of the system;

Fig. 5 is a sectional view substantially on line 5—5 of Fig. 4, certain parts being shown in elevation;

Fig. 6 is a sectional view on the irregular line 6—6 of Fig. 5;

Fig. 7 is a sectional view on line 7—7 of Fig. 5;

Fig. 8 is a sectional view on line 8—8 of Fig. 5; and

Fig. 9 is a sectional view on line 9—9 of Fig. 5.

Referring to the drawings, and to the embodiment of the invention which is illustrated therein, and having reference at first to Fig. 1, there is shown a lubricating system comprising a tank 11, presenting a reservoir for oil. The tank is provided with a filler cap 12, seated on and about a curb 13, which prevents dirt from falling into the oil when the cap is removed for the filling of the reservoir. A screen 14 is provided to prevent the entrance of foreign matter, and to filter the oil. The filling cap is conveniently mounted

for movement to one side by mounting the same on a vertical pin or rod 15, which extends loosely through a cover plate 16, and is encircled by a spring 17 bearing at one end against the under side of the cover plate, and at its other end against a suitable abutment 18 secured to the rod. When the cover is lifted, this spring yields, and after the cover is lifted clear of the curb, the cover may be swung laterally to uncover the screen. The cover plate is conveniently secured to the tank by screws 19. A drain plug 20 near the bottom of the reservoir is provided to drain the oil out of the reservoir, in case it should be necessary at any time.

Leading from and back to the reservoir is a conduit system comprising a plurality of sections of pipe 21, and one or more feeders 22, whose external forms vary somewhat to conform to the requirements of the particular situation where they are to be used. For example, the feeder may be a through feeder, designated by the additional character *a*, an elbow feeder 22*b*, a dead-end feeder 22*c*, or a T feeder 22*d*,—or several through feeders 22*e* may be combined end to end in a gang, where several feeders are closely grouped.

The feeder illustrated in Figs. 2 and 3 described and claimed in my co-pending application, Ser. No. 338,547, filed February 8, 1929, is one of the through feeders, which is interposed between and connects two pipe sections 21, and is coupled thereto by unions 23. The feeder comprises a body or casing 24, provided with a through passage 25, connecting the pipe sections 21 and providing for the passage of oil past this particular feeder. In the case of the dead-end feeder 22*c*, the passage does not extend entirely through. Above the passage 25, there is a small, upwardly-directed opening 26 and a valve seat 27, and above the latter a chamber 28 for a needle valve 29, normally resting on the valve seat and closing the passage 26. This valve is suitably constructed and arranged to respond to a predetermined pressure in the system, as by being loaded with a suitably arranged spring 30. Herein, the lower end of this spring rests against an abutment 31 presented by the valve, and its upper end against

an abutment 32, which is adjustable vertically by a hollow screw 33 threaded into the chamber 28. A steel ball 34, interposed between the abutment 32 and the screw, is provided to insure that the pressure of the spring shall be brought as nearly axial as possible with the valve. The rate of feed is increased by turning the screw in one direction, and diminished by turning it in the other. This 10 varies the load of the spring imposed upon the needle valve.

When the valve opens, oil is admitted from the passage 25 into the chamber 28 thereabove, whence it descends by a lateral passage 35 (see Fig. 3) to a nozzle 36. The rate of feed is readily observable through openings 37 in a casing 38, which is threaded onto the valve casing and holds a tubular glass 39. This casing presents a nipple 40, to be 20 screwed into an appropriate opening in or adjacent the bearing to be lubricated. In some instances, as in the case of the gang of feeders 22e, feed pipes 41 are attached to the nipples by unions 42.

25 Returning now to the tank or reservoir, the latter affords a housing for a pumping unit, designated generally by the numeral 43, having a driving shaft 44, which extends through a bearing bushing 45 and packing 30 gland 46 to the exterior of the casing, where it is provided with a driving element 47, which may be a pulley, or a gear to be connected to and driven by the machine to be lubricated, thus causing the pumping unit 35 to start and stop with the machine. The reservoir may be mounted on or near the machine in any convenient location.

The pumping unit will now be described in detail, reference being had at first to Fig. 5. 40 The principal part is a casting 48, which has a base 49 (see Fig. 9), secured to a pair of lugs 50 upstanding from the bottom of the tank. This casting presents bearings 51 and 52 (see Fig. 5) for the shaft 44. It also presents a pair of pump cylinders 53, and a pair of piston-valve cylinders 54. All of these cylinders are open at the top. The pump cylinders are closed at the bottom by plugs 55, but the piston valve cylinders are open 50 at the bottom to prevent the trapping of oil which would prevent them from moving. Ports 56 connect the pump cylinders 53 with the piston-valve cylinders 54. Inlet and outlet ports 57 and 58 are disposed between, and 55 intersect the piston valve cylinders 54.

There are two pistons 59, one working in each cylinder, and there are two piston valves 60, one working in each piston-valve cylinder. Each piston valve is provided with a 60 reduced portion 61, whose length and location with reference to the piston valve and its relationship with the several ports are such that, in the operation of the pump, oil is drawn into the inlet port 57, and is discharged through the outlet port 58. In the

position of the parts shown in Fig. 5, the left-hand piston 59 is at the lowest point of its stroke, and is ready to start upwardly, while the right-hand piston is at the top of its stroke, and is ready to start in a downward direction. The left-hand piston valve is at mid-point on its upward stroke, and the right-hand piston valve is at mid-point on its downward stroke. Under these circumstances, the left-hand piston has been forcing oil through the left-hand port 56 around the reduced portion of the left-hand piston valve, and into the outlet port 58. Before the left-hand piston starts its up stroke, and before the right-hand piston starts its down stroke, the left-hand piston valve rises and the right-hand piston valve descends. When this happens, the reduced portion of the left-hand piston valve places the left-hand cylinder in communication with the inlet port 57, and the right-hand cylinder in full communication with the outlet port 58. It follows that the next up stroke of the left-hand piston causes oil to be drawn from the inlet port 57 into the left-hand cylinder, and oil to be forced from the right-hand cylinder into the outlet port 58.

The actuation of the pistons is conveniently accomplished by a pair of eccentrics 62 and a pair of eccentric straps 63, encircling the eccentrics and connected by pivots 64 to the pistons. Similarly, the piston valves are actuated by a pair of eccentrics 65, encircled by eccentric straps 66 connected by pivots 67 to the piston valves. While all of the eccentrics might be secured to the shaft if it were desired to operate the pump in only one direction, it is desirable that the pump shall be capable of operation in either direction, for convenience in connecting it up to the machine by which it is to be driven. For this reason, therefore, the eccentrics 65 are secured to a collar 68, which in turn is secured to the driving shaft 44, but the eccentrics 62 are loosely mounted on the shaft 44, and are provided with pins 69 (one of which is well illustrated in Fig. 7), each of which is driven by a collar 70 secured to the shaft and having a lost motion driving connection with the pin, as by providing the collar with a slabbed-off portion 71, the extent of which is such that if the direction of rotation of the collar be reversed, the collar will travel one-half a revolution before it picks up the pin again. This arrangement ensures a proper timing of the pistons with relation to the piston valves, no matter which way the shaft is rotated.

Referring now to Fig. 9, the inlet of the pump is provided with a strainer 75 mounted in a removable ring 76, which is threaded into an intake elbow 77, the latter in turn being threaded into the casting 48, and having a passage 78 communicating with the inlet port 57. The strainer 75 is located close

to the bottom of the reservoir, and strains all of the oil which enters the pump. An outlet pipe 79, threaded into the casting 48 and communicating with the outlet port 58, leads 5 in an upward direction, and as shown in Fig. 1, is connected to the first of the pipe sections 21 of the conduit system.

Referring now to Fig. 8, the return end of the piping system includes a pipe 80, which 10 extends in a downward direction through the cover plate of the reservoir, and is threaded into the casting 48, which is provided with a passage 81 communicating with said pipe and intersecting a passage 82, the latter having 15 an outlet 83 adapted to discharge the returning oil into the reservoir. When this outlet is open, the pump circulates oil through the circuit from the reservoir and back again at a comparatively low pressure (in practice, about four pounds), insufficient to make the feeders respond. When, however, this outlet is closed, as by a valve 84, the pressure in the 20 system rises abruptly to a relatively high pressure (in practice, about sixty pounds), which is sufficient to make the feeders respond. The 25 degree of pressure which is developed in the system when the valve 84 is closed is determined by a pressure relief valve presently to be described. In the present example, the 30 valve 84 is a slowly rotating plate, appropriately driven by and in synchronism with the pump, as by securing the valve by a pin 85 to a worm gear 86, which meshes with and is driven by a worm 87, suitably formed on 35 or secured to the shaft 44. Referring now to Fig. 6, the valve is maintained in firm engagement with the adjacent face of the casting 48, as by securing the valve and the worm gear by the pin 85 to a head 88, presented by 40 a shaft 89, which turns in a bearing 90 presented by the casting, said shaft being constantly urged toward the right, as shown in Fig. 6, by a spring 91 which encircles the shaft, and is interposed between a fixed abutment 92 on the shaft and a washer 93 which 45 rests against the adjacent face of the casting 48. This spring, therefore, constitutes an automatic take-up, which prevents leakage of the valve when the latter is closed.

50 In practice, the valve 84 is closed once in every fifteen revolutions of the pump, and remains closed about 5 per cent. of the time. When the valve is open, the oil has a free circulation, and the pressure is only that required to overcome friction of flow. When 55 the valve is closed, the oil is delivered against a simple pressure relief valve now to be described, as a result of which there is produced in the system a comparatively high pressure for a brief interval of time, the pressure being of sufficient intensity to cause the feeders to respond. If a pressure curve were taken, it would show comparatively long dwells of a pressure insufficient to open the feeders, and 60 comparatively short periods of pressure 65

sufficient to open the feeders. Referring to Fig. 8, there is provided a pressure relief valve designated generally by the numeral 93, the same comprising a casing 94 threaded into the casting 48, and having a passage 95 70 communicating with a short passage 96, which in turn communicates with the passage 82. The passage 95 terminates at its upper end in a valve seat 97, which is controlled by a valve 98 working in a cylindrical chamber 99. Above this valve is a comparatively stiff spring 100, whose lower end is seated in a chamber 101 provided in the upper end of the valve, and whose upper end rests against an abutment 102 presented by a plunger 103, 75 which is guided by a cap 104 threaded onto the valve casing 94. A comparatively light spring 105 is interposed between the abutment 102 on the plunger and an abutment 106 presented by the cap 104. A button 107 80 is attached to the upper end of the plunger.

When the mechanically-actuated valve 84 85 closes the outlet 83 at the return end of the circuit, and the pressure consequently rises, the valve 98 is lifted. Inasmuch as the spring 105 is lighter than the spring 100, the former yields to the greater extent under the influence of the pressure. The venting or relief of the valve is conveniently accomplished 90 by providing the valve with a longitudinal passage 108, constantly communicating with the passage 95 and one or more, herein several radial passages 109 leading to a circumferential groove 110. The valve casing is provided with a relief port 111, shown in dotted lines in Fig. 8, and in full lines in Fig. 1. The inner end of this port is only slightly above the circumferential groove 110, and when the valve is lifted against the resistance presented by the spring 105, the groove registers 100 with the port, and the pressure is relieved by the escape of oil through the relief port 111. The stream of oil which escapes from the relief port is utilized to lubricate some parts of the pump. Some oil runs down and lubricates the upper ends of the pistons and piston valves, as well as the wrist-pins. As 105 shown in Fig. 1, the stream is directed upwardly across the tank to the opposite side of the latter, where it strikes the wall, and oil descends into an oil hole 112 in the shaft bearing 45. The stream also strikes a depending screw or rod 113 above the bearing 51, and directs oil into an oil hole 114 (see Fig. 5) in the bearing 51. The stream also 110 spatters oil onto the eccentrics and their straps thus keeping them constantly bathed with oil. The stream also lubricates the shaft bearing 52, which, as shown in Fig. 5, is provided with an oil hole 115.

115 Referring again to the relief valve, a certain amount of oil leaks past the valve 98 into the chamber 99 above the latter, and this chamber must be vented to prevent the accumulation of oil therein, which would inter- 120 125 130

fere with the proper action of the valve. This venting is accomplished by two vent ports 116 and 117 (see Fig. 4). The oil which issues from the port 116 is utilized to lubricate the shaft 89, and to this end, the bearing 90 is provided with an oil hole 118, which receives oil from the port 116. The oil which is discharged from the port 83 is utilized to lubricate the worm and worm gear. Thus, it is apparent that the pump is self lubricating.

Referring again to Fig. 8, the button 107 furnishes a visual indication of the integrity of the system, because it rises and falls with the pressure pulsations. If the oil supply were exhausted, or if the pump were not functioning or not developing a proper pressure, the button would not rise and fall. Similarly, if the oil line were broken, badly 20 leaking or clogged, there would be no return of oil, and the button would remain dormant. This unique feature is of great practical value, because the operator of the machine, or oil-wright, need only glance at the button 25 to be assured as to the lubrication of the machine.

In practice, the button is marked with the word "Flush". By depressing the button, the spring 100 is compressed, thereby loading the relief valve heavily, so that the pulsation pressure is greatly increased, with a corresponding increase in the amount of oil fed to all of the bearings. This simultaneous flushing is advantageous when starting a machine which has been idle for some time, or if exceptionally difficult starting conditions must be met. When the button is released, the pressure is automatically restored to normal, and the established feed rates are 40 resumed.

The general operation of the system should be evident without further description. The pump, belted or geared to a moving part of the machine which is to be lubricated, starts 45 with it and supplies fresh oil to the feeders. Each feeder, adjusted to the number of drops per hour called for by the bearing which it serves, can be checked in an instant by the department oil-wright or machine operator, 50 because each feeder is provided with a sight feed. The person in charge knows that each operating system under his care is functioning as a whole, because he sees the indicating and flushing plunger reciprocate. When the 55 machine is running, the system delivers oil in predetermined amounts to each bearing, the amount of each of course being predetermined by adjustment of its spring-loading screw 33. When the machine is idle, no oil 60 is delivered. When the machine is running, the system is operated at a speed proportional to the speed of the machine, and furnishes the correct amount of oil to the bearings. The use of the system is characterized by 65 economy of oil, because the feed is propor-

tional to the requirements of the machine. By the accurate and independent adjustment of the amount of the feed rate at each lubrication point, from two to three drops per hour to substantially a stream, it is possible to deliver a minimum amount of oil consistent with safety. The system provides against waste, as well as against excess of oil.

The quick pressure impulse of high intensity and the resulting jump of the needle of the feeder produces a measurable feed of short duration, taken from a circulating supply of lubricant. This makes possible much lower feed rates than heretofore regarded as safe. The jump of the feeder needle overcomes any tendency of the oil to form a film over the feed opening. The fact that this opening is above the horizontal column of oil tends to safeguard the opening from the entrance of foreign matter, which might be 85 in the pipe system. Moreover, the upward flow of oil through the seat clears it of obstructions, which would not be the case if the flow were downward. In this manner, grit or dirt of any sort is harmlessly carried to 90 the reservoir, where it is filtered out. Since the number of pulsations per minute is proportional to the speed of the pump, the amount of oil fed to the bearings is in direct 95 ratio to the speed of the machine.

Reference is made to my copending application, Ser. No. 338,548, filed February 8, 1929, wherein the method is claimed. Reference is also made to my copending application, Ser. No. 338,549, filed February 8, 1929, 100 wherein the apparatus disclosed herein is also disclosed and claimed, in combination with other elements.

Having thus described one embodiment of the invention, but without limiting myself thereto, what I claim and desire to secure by Letters Patent is:

1. Lubricating apparatus comprising, in combination, a circuit conduit system, one or more feeders supplied thereby, means to circulate lubricant in said system under a pressure insufficient to cause said feeder or feeders to feed, and means to cause an intermittent increase of pressure in said system sufficient to cause said feeders to feed.

2. Lubricating apparatus comprising, in combination, a circuit conduit system, one or more pressure-responsive feeders supplied thereby, means to circulate lubricant in said system under a pressure insufficient to cause said feeder or feeders to respond, and means to cause an intermittent increase of pressure in said system sufficient to cause said feeders to feed.

3. Lubricating apparatus comprising, in combination, a circuit conduit system, one or more pressure-responsive feeders supplied thereby, and instrumentalities to circulate lubricant in said system and to create therein a fluctuating pressure characterized by 125 130

comparatively long dwells of an amount insufficient to cause said feeder or feeders to respond and comparatively short periods of pressure sufficient to cause said feeders to respond.

4. Lubricating apparatus comprising, in combination, a conduit system, a pump for producing pressure in said system, a valve cooperating with said pump to cause fluctuation of said pressure, and one or more pressure-responsive feeders supplied by said pump and which open and close in response to said fluctuation.

5. Lubricating apparatus comprising, in combination, a conduit system, a pump for producing pressure in said system, a valve to open and close said system at intervals to cause pulsations of said pressure, and one or more pressure-responsive feeders supplied by said pump and which open and close in response to said pulsations.

6. Lubricating apparatus comprising, in combination, a conduit system, a pump for producing pressure in said system, a pressure-controlling valve, means for operating said valve intermittently to cause pulsations of said pressure, and one or more pressure-responsive feeders supplied by said pump and which have feeding and non-feeding periods corresponding with said pulsations.

7. Lubricating apparatus comprising, in combination, a conduit system, a pump for producing pressure in said system, a valve which opens and closes said system and is not responsive to said pressure, means for operating said valve to cause pulsations of said pressure, and one or more pressure-responsive feeders supplied by said pump and which have feeding and non-feeding periods corresponding with said pulsations.

8. Lubricating apparatus comprising, in combination, a conduit system having an outlet, one or more pressure-responsive feeders supplied thereby, a valve for said outlet, a pump supplying said system and having a capacity insufficient to produce a pressure great enough to cause said feeders to respond when said valve is open, the capacity of said pump being sufficient to produce a pressure great enough to cause said feeders to respond when said valve is closed, and means to open and close said valve intermittently.

9. Lubricating apparatus comprising, in combination, a conduit system having an outlet, one or more pressure-responsive feeders supplied thereby, a valve for said outlet, a pump supplying said system and having a capacity insufficient to produce a pressure great enough to cause said feeders to respond when said valve is open, the capacity of said pump being sufficient to produce a pressure great enough to cause said feeders to respond when said valve is closed, and means to open and close said valve intermittently and to

cause it to remain open longer than it is closed.

10. Lubricating apparatus comprising, in combination, a conduit system having an outlet, a pump for producing pressure in said system, means for closing and opening said outlet, a pressure relief valve for predetermining the maximum pressure when said outlet is closed, and one or more feeders supplied by said conduit system and having means non-responsive to the pressure when said outlet is open but responsive to the pressure when said outlet is closed.

11. Lubricating apparatus comprising, in combination, a conduit system having an outlet, a pump for producing pressure in said system, means for closing and opening said outlet, a pressure relief valve for predetermining the maximum pressure when said outlet is closed, indicating means to furnish an indication of the pressure rise and fall when said outlet is closed and opened, and one or more feeders supplied by said conduit system and having means nonresponsive to the pressure when said outlet is open but responsive to the pressure when said outlet is closed.

12. Lubricating apparatus comprising, in combination, a conduit system having an outlet, a pump for producing pressure in said system, means for closing and opening said outlet, a pressure relief valve for predetermining the maximum pressure when said outlet is closed, indicating means operated by said pressure relief valve to furnish an indication of the pressure rise and fall when said outlet is closed and opened, and one or more feeders supplied by said conduit system and having means non-responsive to the pressure when said outlet is open but responsive to the pressure when said outlet is closed.

13. Lubricating apparatus comprising, in combination, a conduit system having an outlet, a pump for producing pressure in said system, means to open and close said outlet, a pressure relief valve to predetermine the maximum pressure when said outlet is closed, means at will to operate on said relief valve to cause a still greater pressure, and one or more feeders supplied by said conduit system and having means non-responsive to the pressure when said outlet is open but responsive to the pressure when said outlet is closed.

14. Lubricating apparatus comprising, in combination, a conduit system having an outlet, a pump for producing pressure in said system, means to open and close said outlet, a spring-loaded pressure relief valve to predetermine the maximum pressure when said outlet is closed, means at will to place an additional load on said relief valve to cause a still greater pressure, and one or more feeders supplied by said conduit system and having means non-responsive to the pressure when said outlet is open but responsive to the pressure when said outlet is closed.

15. Lubricating apparatus comprising, in combination, a conduit system having an outlet, a pump for producing pressure in said system, means to open and close said outlet, a pressure relief valve having a spring to predetermine the maximum pressure when said outlet is closed, means at will to place a load on said spring to cause a still greater pressure, and one or more feeders supplied by said conduit system and having means non-responsive to the pressure when said outlet is open but responsive to the pressure when said outlet is closed.

16. Lubricating apparatus comprising, in combination, a conduit system having an outlet, a pump for producing pressure in said system, means for opening and closing said outlet, a pressure relief valve for predetermining the maximum pressure when said outlet is closed, means at will to operate on said relief valve to cause a still greater pressure and on the other hand normally operated by said relief valve to furnish an indication of the pressure rise and fall when said outlet is closed and opened, and one or more feeders supplied by said conduit system and having means non-responsive to the pressure when said outlet is open but responsive to the pressure when said outlet is closed.

17. Lubricating apparatus comprising, in combination, a conduit system having an outlet, a pump for producing pressure in said system, means for opening and closing said outlet, a pressure relief valve having a spring to predetermine the maximum pressure when said outlet is closed, means at will to operate through said spring to provide an increased pressure and on the other hand normally operated by said relief valve through said spring to furnish an indication of the pressure rise and fall when said outlet is closed and opened, and one or more feeders supplied by said conduit system and having means non-responsive to the pressure when said outlet is open but responsive to the pressure when said outlet is closed.

18. Lubricating apparatus comprising, in combination, a circuit conduit system, a pump for circulating lubricant in said system, an intermittently operated valve at the return end of said system to cause the pressure therein to rise and fall, and one or more feeders supplied by said system and responsive to the rise and fall of the pressure therein.

19. Lubricating apparatus comprising, in combination, a circuit conduit system, a pump for circulating lubricant in said system, an intermittently operated valve at the return end of said system to cause the pressure therein to rise and fall, a pressure predetermining valve also at the return end of said system to predetermine the maximum pressure, and one or more feeders supplied by said system and responsive to the rise and fall of the pressure therein.

20. Lubricating apparatus comprising, in combination, a circuit conduit system, a pump for circulating lubricant in said system, an intermittently operated valve at the return end of said system to cause the pressure therein to rise and fall, indicating means at the return end of said system to furnish an indication of the rise and fall of the pressure, and one or more feeders supplied by said system and responsive to the rise and fall of the pressure therein.

21. Lubricating apparatus comprising, in combination, a circuit conduit system, a pump for circulating lubricant in said system, an intermittently operated valve at the return end of said system to cause the pressure therein to rise and fall, a pressure predetermining valve also at the return end of said system to predetermine the maximum pressure, indicating means operated by said pressure predetermining valve to furnish an indication of the rise and fall of the pressure, and one or more feeders supplied by said system and responsive to the rise and fall of the pressure therein.

22. Lubricating apparatus comprising, in combination, a circuit conduit system, a pump for circulating lubricant in said system, an intermittently operated valve at the return end of said system to cause the pressure therein to rise and fall, a pressure predetermining valve also at the return end of said system to predetermine the maximum pressure, means at will to operate on said relief valve to cause a still greater pressure, and one or more feeders supplied by said system and responsive to the rise and fall of the pressure therein.

23. Lubricating apparatus comprising, in combination, a circuit conduit system, a pump for circulating lubricant in said system, an intermittently operated valve at the return end of said system to cause the pressure therein to rise and fall, a pressure predetermining valve also at the return end of said system to predetermine the maximum pressure, means operated by said valve to indicate the rise and fall of the pressure, said means being available at will to operate on said relief valve to cause a still greater pressure, and one or more feeders supplied by said system and responsive to the rise and fall of the pressure therein.

24. Lubricating apparatus comprising, in combination, a tank presenting a reservoir for the lubricant, a cover for said tank, a conduit system having an outlet from said tank and an inlet to said tank both below said cover, a pump in said tank for pumping lubricant from said reservoir through said system and back to said reservoir, means within said tank to cause the pressure in said system to rise and fall, a pressure relief valve within said tank to relieve the pressure in said system, said valve discharging into said reservoir, and one or more feeders supplied by said

system and responsive to the rise and fall of the pressure therein.

25. Lubricating apparatus comprising, in combination, a tank presenting a reservoir for the lubricant, a cover for said tank, a conduit system having an outlet from said tank and an inlet to said tank both below said cover, a pump in said tank for pumping lubricant from said reservoir through said system and back to said reservoir, means within said tank to cause the pressure in said system to rise and fall, a pressure relief valve within said tank to relieve the pressure in said system, said valve discharging into said reservoir, a pulsation indicator operated by said relief valve and extending upwardly through said cover, and one or more feeders supplied by said system and responsive to the rise and fall of the pressure therein.
- 10 26. Lubricating apparatus comprising, in combination, a conduit system, one or more feeders communicating therewith, and a pressure relief valve for relieving the pressure in said system, said valve having means for directing some of the lubricant to working parts of said pump to lubricate the same.

- 20 27. Lubricating apparatus comprising, in combination, a conduit system, one or more feeders communicating therewith, a tank, a pump within said tank for pumping lubricant from said tank into said system and back to said tank, and a pressure relief valve for relieving the pressure in said system, said valve having means for supplying lubricant to working parts of said pump to lubricate the same.

In testimony whereof, I have signed my name to this specification.

FREDERICK C. BLANCHARD.
